US00D458376S

(12) **United States Design Patent** (10) Patent No.: **US D458,376 S**
(45) Date of Patent: ** Jun. 4, 2002

(54) **CARDIAC ELECTRODE**

(75) Inventors: **Cameron Rouns**, South Jordan, UT (US); **Netty DiViesti**, Pocatello, ID (US)

(73) Assignee: **Kimberly-Clark Worldwide, Inc.**, Neenah, WI (US)

(**) Term: **14 Years**

(21) Appl. No.: **29/140,850**

(22) Filed: **Apr. 26, 2001**

(51) LOC (7) Cl. **24-01**

(52) U.S. Cl. **D24/168**

(57) **CLAIM**

We claim the ornamental design for the cardiac electrode, as shown and described.

DESCRIPTION

FIG. 1 is a perspective view of the present invention, illustrating the gel portion surrounded by the insulating ring; FIG. 2 is a bottom side view of the present invention; FIG. 3 is a front plan view of the present invention; FIG. 4 is a back plan view of the present invention; and, FIG. 5 is a side view of the present invention. The broken line, indicating an electrical conductor, which is shown in FIGS. 1, 3, 4 and 5, is for illustrative purposes only and forms no part of the claimed design.
